[57] CLAIM

The ornamental design for a pan or the like for pouring liquids into a drum, as shown and described.

DESCRIPTION

FIG. 1 is a top plan view of a pan or the like for pouring liquids into a drum showing my new design;

FIG. 2 is a front elevational view thereof.

FIG. 3 is an elevational view of one side thereof, with the other side appearing as a mirror image.

FIG. 4 is a bottom plan view thereof.

FIG. 5 is a side elevational view thereof, with a broken line representation of a drum shown for purposes of illustration only.
